UNITED STATES PATENT OFFICE.

JAMES BARLOW AND SPENCER M. ALPAUGH, OF TRENTON, N. J., ASSIGNEES TO SAID ALPAUGH AND FRANK A. MAGOWAN, OF SAME PLACE.

DESIGN FOR AN EARTHENWARE VESSEL.

SPECIFICATION forming part of Design No. 14,388, dated November 6, 1883.

Application filed August 20, 1883. Term of patent 7 years.

To all whom it may concern:

Be it known that we, JAMES BARLOW and SPENCER M. ALPAUGH, citizens of the United States, and residents of Trenton, New Jersey, 5 have invented an original Design for an Earthenware Vessel, of which the following is a specification.

Our design is fully shown in the accompanying drawings, Figure 1 being a side view of the vessel; Fig. 2, a plan view of the same, and Fig. 3 an end view.

The general shape of the vessel is quadrangular with rounded corners, the vessel shown being oblong, although it may be square, or 15 nearly square, without affecting the character of the design. The lid A has a rounded rim, a, immediately adjacent to which is the concave a', terminating at the top in a rib, a'', from which rises the central raised portion or dome, 20 a'', of the lid, the shape of which is that of a flattened ogee. In the center of the lid is a medallion comprising the raised panels b b', the outer or lower panel having nicked corners, but both panels following the general 25 conformation of the lid. From the center of the panel b' rises the handle B, which comprises the base d, the opposite standards or brackets, d', and the ribbed bar d'', the latter having a central spiked band, d''. From each 30 side of the base of the handle project ornaments d''. The body D of the vessel has the concave neck f, which merges into the abrupt swell f' of the breast or upper portion of the body, the lower portion, f'', being contracted 35 and merging at each corner into an outwardly-swelling foot, g, the outline of which is scalloped. On the lower edge of the body, cen-

trally between the feet, are scallops h, and around said lower edge and the feet extends a continuous bead, i. Each end of the vessel 40 has handles B, similar to that on the lid.

We claim—

1. The design for the lid of an earthenware vessel, said design comprising the rim a, concave a', rib a'', and central dome, a'', with central medallion comprising the two quadrangular panels, the outer having nicked corners, 45 as shown and described.

2. The design for the handle B of an earthenware vessel, said design comprising the base 50 d, standards or brackets d', and bar d'', with spiked band d'', as shown and described.

3. The design for the body D of an earthenware vessel, said design comprising the quadrangular shape, the concave neck f, the abruptly-swelling upper portion or breast, f', and the contracted lower portion, f'', merging at each corner into an outwardly-swelling foot, 55 g, as set forth.

4. The design for an earthenware vessel, 60 said design comprising the rectangular body D, with concave neck f, breast f', contracted lower portion, f'', scalloped feet g at the corners, and intermediate scallops, h, as shown and described.

In testimony whereof we have signed our names to this specification in the presence of two subscribing witnesses.

JAMES BARLOW.
SPENCER M. ALPAUGH.
